UNITED STATES PATENT OFFICE.

WILLIAM S. PATTISON, OF DENVER, COLORADO.

MECHANICAL STARTER FOR INTERNAL-COMBUSTION ENGINES.

1,127,804.

Specification of Letters Patent.

Patented Feb. 9, 1915.

Application filed February 25, 1914. Serial No. 821,073.

To all whom it may concern:

Be it known that I, WILLIAM S. PATTISON, a citizen of the United States, residing at Denver, in the county of Denver and 5 State of Colorado, have invented a certain new and useful Mechanical Starter for Internal-Combustion Engines, of which the following is a specification.

The object of my invention is to provide 10 a mechanical starter for internal combustion engines, particularly for those used on motor vehicles, of simple, durable and inexpensive construction.

More particularly, it is my object to provide 15 such a starter so constructed and arranged that the engine may be turned over by the direct pull upon a lever located convenient to the driver.

Still a further object is to provide such 20 a starting device so constructed and arranged that should the engine "kick back" during the time when the operator is pulling the lever no injury will occur to the operator.

25 A further object is to provide such a device of compact construction arranged to be readily and easily attached to an ordinary automobile.

My invention consists in certain details, 30 in the construction, arrangement and combination of the various parts of the device, whereby the objects contemplated are attained, as hereinafter more fully set forth, pointed out in my claims, and illustrated in 35 the accompanying drawings, in which:

Figure 1 shows a top or plan view of an engine mounted on a motor vehicle and equipped with a starting device embodying my invention, part of the vehicle only being 40 shown. Fig. 2 shows a front elevation of the same. Fig. 3 shows a vertical, longitudinal, detail, sectional view with portions of the starter, the starter shaft and pulley thereon being shown in side elevation taken 45 on the line 3-3 of Fig. 1. Fig. 4 shows an enlarged, vertical, sectional view of the clutch of the starter, and Fig. 5 shows a transverse, sectional view taken on the line 5-5 of Fig. 1.

50 In the accompanying drawings, I have used the reference numeral 10 to indicate generally the frame of the motor vehicle having a dash 11 and engine 12 from which

projects forwardly the engine shaft 13. In Fig. 2 is shown the radiator 14.

55 Suitably mounted in two-part bearings 15 on the engine base is a starter shaft 16. Formed on the engine shaft 13 is a clutch member 17. Mounted on the end of the engine shaft and extending beyond it, is a sleeve 18 having at its outer end an inwardly extending flange 19. Mounted on the end of the starter shaft 16, adjacent to the end of the engine shaft 13, is a clutch member 20 which is received within the 60 sleeve 18. Formed on the outer end of the starter shaft 16 is a clutch member 22 having comparatively shallow teeth 23. The clutch member 22 is of greater diameter than the shaft 16. Screwed through the 65 center of the clutch member 22 and into the end of the shaft 16 is a smaller shaft 24.

70 Mounted on the shaft 24 is a grooved pulley 25 having formed on its outer surface a small hub 26 which is grooved to form a 75 pulley and having on its other side an elongated hub 27 provided with screw threads 28 of comparatively wide pitch. Formed on the inner end of the hub 27 is a clutch member having teeth 29 comparatively shallow 80 and designed to coact with the teeth 23 of the clutch member 22.

75 Mounted on the screw threaded portion of the hub 27 is a sleeve 30 internally screw threaded to coact with the screw threads 28 85 and extending to a position in which it receives the outer end of the shaft 16. The sleeve 30 is provided at its inner end with an inwardly extending annular flange 31, forming a bearing for the shaft 16. Resting 90 against the flange 31 and spaced from the clutch member 22 is a washer 32. Mounted on the shaft 16 and arranged to rotate therewith is a flange cup 33 which receives the flange 31 and the end of the sleeve 30. The 95 wall of the cup 33 is split and said cup is made of somewhat resilient metal and is designed to frictionally grip the sleeve. At its outer end the sleeve 30 is provided with an outwardly extending annular flange 34 100 formed on the outer end of which is a cylindrical annular flange 35 spaced apart from the hub 27. The flange 35 is formed with a notch 36 in its outer edge which will be hereinafter more fully referred to. A 105 detachable pin 37 is extended through the

pulley 25 from the outside and into the notch 36. In the outer end of the pin 37 is a head 38.

Secured to the engine base and extending forwardly therefrom is a bracket 39. Mounted in the bracket 39 is a vertically arranged pulley 40 in the same vertical plane as that in which the pulley 25 rests and preferably below the level of the upper edge 10 of the pulley 25.

Mounted on the bracket 39 is a horizontal sleeve 41 arranged with its longitudinal axis at right angles to that of the shaft 24 and slightly below the level of the middle of 15 said shaft 24. Slidably but nonrotatably mounted in the end of the sleeve 41 farthest from the sleeve 30 is a short cylindrical rod 42 having bifurcated arms 43 formed on its outer end to receive between them a horizontally mounted pulley 44 rotating on a 20 short shaft 45 extending through the arms 43. The pulley 44 is substantially on a level with the lower edge of the radiator 14. The wall of the sleeve 41 is preferably made 25 thicker for a portion of its length adjacent to the sleeve 30, thereby forming an internal shoulder 46.

Within the sleeve 41, the cylindrical rod 42 is reduced in diameter at 47. Slidably 30 mounted on the reduced portion 47, within said cylinder 41, is a collar 48. Mounted on the reduced portion 47, between the collar 48 and the body 42, is a powerful coil spring 49. The movement of the collar 48 away 35 from the body 42 is limited by a shoulder formed on the reduced portion 47, as shown in Fig. 5.

At its inner end the sleeve 41 is provided with an inwardly extending flange 53 which 40 forms a bearing for the reduced portion 47. The reduced portion 47 extends beyond the sleeve 41, at the end opposite the body 42, as shown in Fig. 5. Formed on the portion which so extends beyond the sleeve 41 are 45 screw threads 50 on which is mounted a nut 52, whereby the movement of the body 42 and reduced portion 47 away from the sleeve 30 is limited.

Mounted on the reduced portion 47, between the flange 53 and the collar 48 is a weaker coil spring 54. The lengths of the spring 49 and the spring 54 are such that the spring 54 normally holds the collar 48 slightly spaced away from the shoulder 46, as shown in Fig. 5. Pivoted in the outer end of the reduced portion 47 is a removable device or end 55 designed to swing in a vertical plane from horizontal position in line with the reduced portion 47 downwardly and normally held in horizontal position by means of a spring 56. The movable device 55 is provided at its forward end with a sharp edge 57 normally spaced slightly apart from the flange 35, the purpose of which will be hereinafter explained.

Secured to the periphery of the pulley 25 is a flexible device 58 which is extended over the top of the pulley 25, then below and around the pulley 40, around the pulley 44 and through a guide device 59, adjacent to 70 the pulley 44, through the dash 11 to a lever 60 suitably located and preferably pivotally mounted within the motor car and adjacent to the driver's seat where it will be 75 convenient for access.

Mounted on one of the frame members 10 is a horizontal pulley 61 preferably in a horizontal plane level with the top or bottom of the grooved hub 26. Secured to the frame 10 in the rear of the pulley 61, is a 80 coil spring 62. Secured to the head 38 of the pin 37 is a flexible device 64 which is extended around the pulley 61 and is secured to the spring 62.

I shall now describe the practical operation of my improved starter: Assuming that it is desired to crank the engine and that the lever 60 is at the forward position of its movement, said lever is grasped and drawn quickly rearwardly. The flexible device 58 rotates the pulley 25. The pulley 25 normally stands in such a position that the hub 27 is at its outward position of movement with relation to the sleeve 30. The outward movement of the pulley 25 longitudinally on the shaft 24 is limited by the movement of the pin 37 in the notch 36. The notch 36 is of such length that the pin 37, while it limits the rotary movement of the pulley 25, and the hub 27 with relation to the sleeve 30, still permits enough of said rotary movement to permit the coacting screw threads on the hub 27 and within the sleeve 30 to move the clutch members formed on the hub 27 and the shaft 16 to move into or out of 95 engagement as the case may be. When the lever 60 is drawn back and the pulley 25 is rotated, the hub 27 rotates within the sleeve 30, thereby bringing the clutch members last above mentioned into operative relation 100 with each other. The movement of the sleeve 30 with the pulley 27 is prevented by a frictional engagement of the flange 31 with the parts adjacent thereto. At about 105 the same time when said clutch members engage the pin 37 engages the flanges 35 at 110 one end of the notch or slot 36, whereby, during the rest of the rearward movement of the lever 60, the sleeve 30 is rotated with the hub 27. 115

It will of course be seen that during the larger part of the movement of the lever 60 on account of the engagement of the clutch members hereinbefore referred to, the shaft 16 and the shaft 13 will be rotated with the hub 27 and the engine will be thereby turned over.

On the rearward movement of the lever 60, the flexible device 64 is wound upon the hub portion 26 and if the engine does not 120 125 130

start the lever may be returned to starting position and the spring 62 and flexible device 64 will rotate the pulley 25 to its original position. The parts are so arranged 5 that when the lever 60 is drawn back, the pulley 25 is rotated in the direction indicated by the arrows in Figs. 5 and 2 which is the same direction as that of the rotation of the engine shaft. If the engine starts 10 during the rearward movement of the lever, the clutch members on the shaft 16 and the hub 27 are disengaged in the following manner.

The rotation of the engine shaft from the 15 engine tends to rotate the parts in the direction indicated by the arrows. The frictional engagement of the cap 33 with the sleeve 30 will cause said sleeve to rotate with the shaft 16 faster than the hub 27 rotates, and on account of the action of the screw threads on the hub 27 and sleeve 30 the clutch members will be moved apart.

If the engine should "kick back" during 20 the cranking operation, the clutch members are disengaged in the following manner: The spring 49 is of such strength that for ordinary cranking purposes the collar 48 is forced against the shoulder 46, but the spring 49 is not substantially contracted. 25 If, however, the engine should "kick back" while the lever is being pulled back, the shafts will be rotated in the direction opposite to that indicated by the arrows on Figs. 5 and 2, and a powerful jerk will be 30 imparted to the pulley 44 and the member 42 and will cause the spring 49 to be contracted, forcing the member 55 against the flange 35, thereby rotating the sleeve 30 in the direction indicated by the arrow in Fig. 35 5 and the direction opposite to the rotation of the hub 27, causing the clutch members to disengage.

It will be understood that some changes 40 may be made in the details of the construction of my starting device without departing from its essential features, and it is my intent to cover by this application any such changes as may be included within the scope 45 of the appended claims.

50 I claim as my invention:

1. In a device of the class described, a support, a starter shaft rotatably mounted thereon and designed to be operatively connected with an engine shaft, a clutch member formed on said starter shaft, a shaft mounted in the end of said starter shaft, a hub mounted on said last named shaft provided with external screw threads and having a clutch member formed on its end adjacent to the clutch member on the starter shaft, an internally screw threaded sleeve mounted on said hub and rotatably, but non-slidably mounted on said starter shaft, means on said sleeve and said hub for limiting their rotary movement with relation to 55 each other so that at one limit of their relative movement the clutch members are engaged, while at the other limit they are disengaged, and means for imparting rotary movement to said hub.
2. In a device of the class described, a support, a starter shaft rotatably mounted thereon and designed to be operatively connected with an engine shaft, a clutch member formed on said starter shaft, a shaft 70 mounted in the end of said starter shaft, a hub mounted on said last named shaft provided with external screw threads and having a clutch member formed on its end adjacent to the clutch member on the starter shaft, an internally screw threaded sleeve mounted on said hub and rotatably, but non-slidably mounted on said starter shaft, means on said sleeve and said hub for limiting their rotary movement with relation to 75 each other so that at one limit of their relative movement the clutch members are engaged, while at the other limit they are disengaged, and means for imparting rotary movement to said hub, 80 said means comprising a pulley on the hub, a flexible device mounted on the pulley, and a lever operatively connected with said flexible device.
3. In a device of the class described, a support, a starter shaft rotatably mounted 85 thereon and designed to be operatively connected with an engine shaft, a clutch member formed on said starter shaft, a shaft mounted in the end of said starter shaft, a hub mounted on said last named shaft provided with external screw threads and having a clutch member formed on its end adjacent to the clutch member on the starter shaft, an internally screw threaded sleeve mounted on said hub and rotatably, but non-slidably mounted on said starter shaft, 90 means on said sleeve and said hub for limiting their rotary movement with relation to each other so that at one limit of their relative movement the clutch members are engaged, while at the other limit they are disengaged, and means for imparting rotary movement to said hub, 95 said means comprising a pulley on the hub, a flexible device mounted on the pulley, and a lever operatively connected with said flexible device.
4. In a device of the class described, a support, a starter shaft rotatably mounted 100 thereon and designed to be operatively connected with an engine shaft, a clutch member formed on said starter shaft, a shaft mounted in the end of said starter shaft, a hub mounted on said last named shaft provided with external screw threads and having a clutch member formed on its end adjacent to the clutch member on the starter shaft, an internally screw threaded sleeve mounted on said hub and rotatably, but non-slidably mounted on said starter shaft, 105 means on said sleeve and said hub for limiting their rotary movement with relation to each other so that at one limit of their relative movement the clutch members are engaged, while at the other limit they are disengaged, and means for imparting rotary movement to said hub, 110 said means comprising a pulley on the hub, a flexible device mounted on the pulley, a lever operatively connected with said flexible device, and yielding means for returning the parts to their starting positions after they have been moved by means of the lever.
5. In a device of the class described, a support, a starter shaft rotatably mounted 115 thereon and designed to be operatively connected with an engine shaft, a clutch member formed on said starter shaft, a shaft mounted in the end of said starter shaft, a hub mounted on said last named shaft provided with external screw threads and having a clutch member formed on its end adjacent to the clutch member on the starter shaft, an internally threaded sleeve mounted 120

- on said hub and rotatably but non-slidably mounted on said starter shaft, means on said sleeve and said hub for limiting their rotary movement with relation to each other so that at one limit of their relative movement the clutch members are engaged while at the other limit they are disengaged, means for imparting rotary movement to said hub, said means comprising a pulley on the hub, a flexible device mounted on the pulley, a lever operatively connected with said flexible device, yielding means for returning the parts to their starting positions after they have been moved by means of the lever, and means for retarding the rotary movement of said sleeve.
5. In a device of the class described, a support, a starter shaft rotatably mounted thereon and designed to be operatively connected with an engine shaft, a clutch member formed on said starter shaft, a shaft mounted in the end of said starter shaft, a hub mounted on said last named shaft provided with external screw threads and having a clutch member formed on its end adjacent to the clutch member on the starter shaft, an internally threaded sleeve mounted on said hub and rotatably but non-slidably mounted on said starter shaft, means on said sleeve and said hub for limiting their rotary movement with relation to each other so that at one limit of their relative movement the clutch members are engaged while at the other limit they are disengaged, means for imparting rotary movement to said hub, said means comprising a pulley on the hub, a flexible device mounted on the pulley, a lever operatively connected with said flexible device, yielding means for returning the parts to their starting positions after they have been moved by means of the lever, means for retarding the rotary movement of said sleeve, and said means comprising a device slidably mounted and having a part arranged in the path of said flexible device and a part designed to be moved against said sleeve when the flexible device is drawn taut, and yielding means on said slidably mounted device for limiting the movement thereof toward said sleeve.
10. a flexible device mounted on the pulley, a lever operatively connected with said flexible device, yielding means for returning the parts to their starting positions after they have been moved by means of the lever, and means for retarding the rotary movement of said sleeve.
15. means for retarding the rotary movement of said sleeve.
20. a flexible device mounted on the pulley, a lever operatively connected with said flexible device, yielding means for returning the parts to their starting positions after they have been moved by means of the lever, and means for retarding the rotary movement of said sleeve.
25. a flexible device mounted on the pulley, a lever operatively connected with said flexible device, yielding means for returning the parts to their starting positions after they have been moved by means of the lever, and means for retarding the rotary movement of said sleeve.
30. a flexible device mounted on the pulley, a lever operatively connected with said flexible device, yielding means for returning the parts to their starting positions after they have been moved by means of the lever, and means for retarding the rotary movement of said sleeve.
35. a flexible device mounted on the pulley, a lever operatively connected with said flexible device, yielding means for returning the parts to their starting positions after they have been moved by means of the lever, and means for retarding the rotary movement of said sleeve.
40. a flexible device mounted on the pulley, a lever operatively connected with said flexible device, yielding means for returning the parts to their starting positions after they have been moved by means of the lever, and means for retarding the rotary movement of said sleeve.
45. path of said flexible device and designed to be drawn against said sleeve when said lever is moved to pull on the flexible device for rotating the pulley.
50. 6. In a device of the class described, a support, a starter shaft rotatably mounted thereon and designed to be operatively connected with an engine shaft, a clutch member formed on said starter shaft, a shaft mounted in the end of said starter shaft, a hub mounted on said last named shaft provided with external screw threads and having a clutch member formed on its end adjacent to the clutch member on the starter shaft, an internally threaded sleeve mounted on said hub and rotatably but non-slidably mounted on said starter shaft, means on said sleeve and said hub for limiting their rotary movement with relation to each other so that at one limit of their relative movement the clutch members are engaged while at the other limit they are disengaged, means for imparting rotary movement to said hub, said means comprising a pulley on the hub, a flexible device mounted on the pulley, a lever operatively connected with said flexible device, yielding means for returning the parts to their starting positions after they have been moved by means of the lever, means for retarding the rotary movement of said sleeve, and said means comprising a device slidably mounted and having a part arranged in the path of said flexible device and a part designed to be moved against said sleeve when the flexible device is drawn taut, and yielding means on said slidably mounted device for limiting the movement thereof toward said sleeve.
55. 70. 75. 80. 85.
